UNITED STATES PATENT OFFICE.

CLARENCE E. CROZIER, OF DES MOINES, IOWA.

FLOOR CONSTRUCTION.

Original application filed October 30, 1925, Serial No. 65,863. Divided and this application filed December 27, 1926. Serial No. 157,342.

The invention relates to floor construction embodying among other characteristics pan moulds having supporting means upon the meeting edges thereof to provide a rigid support and a leak-proof joint for the moulded material.

More specifically stated, the supporting means contemplates channel portions for the reception of spreading means to sustain the pans in position.

This case is a division of my patented invention, filed October 30, 1925, Serial No. 65,863, patented December 28, 1926, and bearing the Patent Number 1,612,704, and which embodies a species of invention previously divided from the above entitled patent.

With the above and other objects in view, the invention further includes the following novel features and details of construction, to be hereinafter more fully described, illustrated in the accompanying drawings, and pointed out in the appended claims.

In the drawings:

Figure 1 is a transverse section of the pan moulds in use.

Figure 2 is a perspective of the pans.

Figure 3 is a similar view of a tapered end pan.

Referring to the drawings in detail, where in like characters of reference denote corresponding parts, the reference character 10 indicates a pan preferably substantially U-shaped in cross section and which provides outwardly and obliquely disposed side walls 11.

The lower edges of said side walls 11 are bent outwardly to provide supporting flanges 12, transversely disposed with respect thereto and in spaced parallel relation to the top of the pan. The flanges 12 when disposed in juxtaposition to companion flanges carried upon the meeting side edges thereof provides a socket within which supporting beams 13 are positioned, substantially as illustrated in Figure 1 of the drawings.

Elongated and angularly disposed plates 14 are carried upon the undersides of the flanges 12 and extend axially of the longitudinal centers thereof. The offset portions of said angle plates are inwardly disposed while the upright portions thereof abut the opposed side edges of the supporting beams 13, said beams being thus held against displacement.

The disposition of the angle plates 14 upon

the flanges 12 and the offset portion of said angle plates disposed in direct alinement with the sides 11 of the pans 10 define channel portions 15 within which the opposed ends of spreading means, such as illustrated in Figure 1 of the drawing, are received to prevent said plates from buckling and to retain the same upon the supporting beams 13. The spreading means also carries supporting members for engagement with the undersides of the top of said pan to prevent the same from bending under the weight of the material poured thereon. The moulded material is preferably concrete and in the instance of constructing floors it is desired to enlarge and strengthen the joists moulded between the adjacent side walls 11 of companion pans, I provide what is termed a tapered end pan 16. The said tapered end pans are of identical construction as that of the pan 10 save for the tapering of the side walls 17 thereof. Flange members and angle plates of identical construction and relative association to those as embodied in the plate or intermediate pan 10 are embodied in the tapered end pans 16.

When moulding the enlarged ends or extremities of the joists abutting a wall, ends 18 are employed for abutting off the reduced end of the tapered end pans 16 to prevent undue loss of the material moulded. The said ends are disposed wholly within the enclosure defined by the pan proper, thereby leaving the channel portions free for the reception of the spreading means therein.

As mentioned in the foregoing, the spreading means consists of a channeled bar 19 adapted to position its respective ends within the channel portions 15 created and formed by the relative association of the flanges 12 and angle plates 14, said channel bar providing elongated slotted portions 20 preferably located at an intermediate point in its length and which is adapted to receive therein the aforementioned uprights indicated at 21. The said upright provides rack teeth 22 upon one side edge thereof for engagement with the edges of said elongated slotted portion 20. These teeth are held in engagement with the particular portion of the channeled spreader bars 19 through the instrumentality of a wedge member 23 dropped behind one side edge of the upright 20 in diametrically opposed relation to that of the rack teeth 22.

From the foregoing description and accompanying drawings, it will be noted that the invention provides an exceedingly useful and advantageous form of moulding apparatus which will effectually and more quickly mould the floors of the modern concrete construction building.

The invention is susceptible of various changes in its form, proportions and minor details of construction, and the right is herein reserved to make such changes as properly fall within the scope of the appended claims.

Having thus described the invention, I claim:

- 15 1. A floor construction comprising pan moulds having downwardly and obliquely disposed side walls terminating in outwardly and transversely disposed flanges, and angle plates carried by the flanges.
- 20 2. A floor construction comprising pan moulds having downwardly and obliquely disposed sides terminating in outwardly and

transversely disposed flanges, and angle plates disposed longitudinally of and upon the undersides of said flanges.

25

3. A floor construction comprising pan moulds having downwardly and obliquely disposed side walls, said walls terminating to provide outwardly and transversely disposed flanges, angle plates depending therefrom, said flanges and plates forming channel portions therebetween, and the angle plates being disposed in spaced relation to the side edges of the flanges.

4. A floor construction comprising end and intermediate pan moulds, said pans being adapted for relative association in end to end and parallel relation, the meeting edges of said pans provide supports therefor, and plates adapted to be carried within the reduced ends of the tapered end portion to terminate a mould of a desired length.
